UNITED STATES PATENT OFFICE

WILLIAM P. ARON, OF DALLAS, TEXAS, ASSIGNOR, BY MESNE ASSIGNMENTS, TO W. D. KENNEDY, OF DALLAS, TEXAS

VENTILATING AND AIR-PURIFYING UNIT

Application filed January 19, 1928. Serial No. 243,002.

This invention relates to ventilating fans and it refers more particularly to a combined ventilating and air purification device, the principal object residing in the provision of such a device as designated capable of establishing proper circulation of air in an inclosure, and provided with facilities by which any known insecticide, air purifying chemical, deodorizer or perfume may be distributed by the draft created by the fan in a minimum of time, thoroughly and uniformly without waste or effort.

The invention further aims among its objects to provide a fan having a very pleasing and decorative effect, combined with its utilitarian features, its particular form however, by which this effect is obtained being not only for ornamental purposes but likewise aiding in the proper directing of air currents by a fan proper and from which maximum results are obtained in both, ventilating and purifying the confined air.

Still further the invention comprehends among its objects the provision of an improved type of ventilating and air purifying unit, particularly adaptable for use in business establishments difficult to ventilate, such as theaters, auditoriums, storage rooms, and even hospitals and the like, the novel arrangement by which to discharge the chemical purifying medium contained within the fan being such as to permit such discharge as is necessary or desired to clarify the air without undue effort.

With the foregoing objects as paramount, the invention has especial reference to its salient features of construction and operation of parts by which said objects are attained, to become manifest as the description proceeds, taken in connection with the accompanying drawings, wherein:-

Figure 1 represents a side elevational view of a ventilating and air purifying fan constructed according to the present invention.

Figure 2 is a sectional side elevational view of the fan shown in Figure 1, and Figure 3 is a view on lines 3—3 of Figure 2.

Continuing now more in detail with the drawings, it may be here stated that it is

preferred, to obtain the desired effect, both as regards the ornamental design and proper handling of air, to construct the body of the fan to typify in miniature form an aerial torpedo, such design affording, as obvious, a gradual, rather than abrupt recession of the body from the nose of the device, which enables the maximum effect to be obtained from the action of the fan proper rearwardly of the body, in taking up and distributing the substance expelled in the manner hereinafter described.

The body of the device is composed of three essential elements; the electric motor 1, fuselage 2 and nose 3, with a fan proper 4 constructed according to the conventional airplane propeller, formed to indicate a continuation of the nose 3 for the sake of symmetry and appearance. The fuselage 2 is provided with conventionally arranged wings 5, in the present case directing the currents of air produced by the fan 4.

The means for suspending the invention is shown in Figures 1 and 2 as being in the form of an interiorly threaded boss 6 affixed to the motor 1 into which a short section of metal conduit 7 is threaded. A lock nut 8 is provided to positively prevent unscrewing of the connection thus made. As apparent in these figures, the suspending conduit 9, through which passes the current wires 10 is connected to the section 7 in such a manner as to provide an adjustment in the horizontal plane of the fan. A corrugated lock washer 11, and a co-operating nut 12 is provided to hold the joint against displacement.

It is obvious that the particular form of the fan is such as to create the maximum in air circulation, and to obtain the best results, the front of the device is directed toward the entrance of a building to enable the fan proper 4 to pull the air through the building.

Referring now to the means contained within the fan for the purpose of perfuming and purifying the confined air, which forms the essential features of the invention, attention is directed to Figure 2, showing in cross section a tank 13 situated within the fuselage 100

2, and having a flanged head 14, arranged in such a manner as to provide an annular confined space 15 about the tank 13, in which space is placed certain kinds of chemical disinfectant of pleasing odor. A filler opening 16 is provided by which such chemical is inserted. The chemical contained within the said outer space 15 is usually of a congealing, slow evaporating nature and the fuselage is perforated at 17 to permit release of fumes emitted by the deodorant or disinfectant in said space 15.

10 The tank 13 is proposed to contain a liquid chemical such as insecticide, air purifier and the like, and is filled through opening 18 as shown in Figure 2, and tube 20. Entering the tank 13 at the opposite end is a tube 21, so curved interiorly of the tank as to receive fluid at its lowest point, and direct the same through adjustable spray nozzle 22 at the extreme rear end of the fuselage. Air directed rearwardly by the fan 4, due to the streamline body of the fan, catches up the spray of fluid emitted from the spray nozzle 22 and carries it the full extent of the force of the fan 4.

15 The means to effect such discharge of fluid is of the atomizer type, which includes a depending tube 23 to which is connected a pressure bulb 24. The opposite end of the tube 23 enters the tank 13 through the flanged head 14, as apparent in Figure 2, and is so arranged as to perform a dual function, i. e., supplying the necessary air pressure in 20 the tank to effect discharge of fluid within the latter upon pressure of bulb 24, and as a switch actuating cord in controlling the electrical circuit to motor 1. The switch is designated by the character 25 in Figure 2 and is of the double acting type, the tube 23 having sufficient slack above the point where it is connected to the switch as to permit the switch to be actuated without affecting the connection between the tube and tank 25 head 14.

20 While no specific manner of wiring is necessary, an example is exemplified in the drawings, which includes the wires 10 extending through conduits 7 and 9, one of 30 which is connected to one of the motor brushes (not shown) while the other extends to switch 25, as shown. Another wire 26 extends from the switch 25 to the other motor brush (not shown).

35 The fan 4 is rigidly affixed to shaft 27 of the motor, affording a direct drive. The motor is provided with oil receptacles 28 of a conventional nature.

40 Manifestly, the construction shown is capable of considerable modification, and such modification as is considered in keeping with the appended claims is also considered within the spirit of the following claims:

45 1. A device of the type set forth including a perforated body formed to receive a

deodorant, radially and longitudinally extending wings on the body, and a rotary fan carried by the body and positioned so as to cause air currents created thereby to be directed by said wings longitudinally of the body and over the perforations.

50 2. A device of the type set forth including a chemical holding body, discharge means for the chemical, motor operated air current creating means for distributing the chemical, and combined means for supplying air under pressure to the chemical to effect discharge thereof and for controlling the motor.

55 3. A device of the type set forth including a chemical holding body, discharge means for the chemical, motor operated air current creating means for distributing the chemical, a switch for the motor, an air conduit connected to the body for conveying air under pressure to the chemical, and means to connect the conduit to the switch so as to cause operation thereof by predetermined movements of the conduit.

60 4. In combination with a chemical holding body having an outlet for the chemical, means carried by the body for generating air currents to distribute the chemical, and combined means to supply air under pressure to the chemical to effect expulsion thereof through the outlet and to control said air current generating means.

65 5. A device of the type set forth including a chemical holding body, discharge means for the chemical, motor operated air current creating means for distributing the chemical, a switch for the motor, a flexible air conduit connected at one end to the body and having its said end curved, and a member connected to the conduit at the base of the curve and connected to the switch whereby to operate the latter by lengthwise movement of the conduit, and means to supply air under pressure to the conduit.

70 In testimony whereof I affix my signature. WILLIAM P. ARON.
